UNITED STATES PATENT OFFICE.

HERMAN A. SCHIOREGGE, OF WAKEFIELD, NEBRASKA.

BAKE-OVEN.

SPECIFICATION forming part of Letters Patent No. 614,898, dated November 29, 1898.

Application filed October 26, 1897. Serial No. 656,452. (No model.)

To all whom it may concern:

Be it known that I, HERMAN A. SCHIOREGGE, residing at Wakefield, in the county of Dixon and State of Nebraska, have invented certain 5 useful Improvements in Bake-Ovens; and I do hereby declare that the following is a full, clear, and exact description of the invention, such as will enable others skilled in the art to which it appertains to make and use the 10 same, reference being had to the accompanying drawings, which form a part of this specification.

This invention has relation to a new and novel improvement in bake-ovens.

15 The object of my invention is to provide a new and novel bake-oven which shall be simple of construction and operation and embody the following advantages and instrumentalities, to wit: a revolving shelf-frame 20 provided with adjustable weights which are incased in a housing provided with solid walls; heating-pipes having end caps, so that said pipes may be readily cleaned; hollow shelves pivotally depending from said shelf-frame; 25 a sliding door which can be opened to permit the least escape of heat; a simple locking mechanism, so that the revolving shelf-frame may be locked at any point, and an interchangeable driving mechanism, so that the 30 shelf-frame may be revolved by spring-motor or other motive power.

The oven is compact and portable, so that it can be readily removed in sections to be replaced, as will be described more fully hereinafter.

35 In the accompanying drawings, Figure 1 is an enlarged front elevation of the improvement. Fig. 2 is a sectional front view of the same on the line 2 2 of Fig. 4. Fig. 3 is a rear elevation of the same. Fig. 4 is a plan view of the improvement with the cover of the baking-chamber removed and with parts in section. Fig. 5 is a perspective view of one of the supporting-pans for the bread, 40 while Fig. 6 is an enlarged transverse section of the improvement, showing a modified form of driving-gear.

45 My invention comprises, essentially, a housing which is preferably provided with a flat bottom and four square sides and an arched dome A', as is shown in Figs. 1, 2, and 3, forming a heating or baking chamber.

These bottom and side sections, as well as the dome or top section, are made separate and of two parts, the spaces between which are 55 filled with asbestos or any other suitable non-heat-conducting material. Each section is provided with a flange or extension M, bolted thereto, the flange extending beyond the packing contained between the double walls. 60 These flanges are so situated that when the sections are assembled in place the sections may be secured together by means of bolts passing through the flanges M.

Within the bottom and upon one side of 65 the chamber I provide a furnace B, having a door B', through which the fuel is fed, a grate B² being positioned at a proper point, as shown in the drawings. The products of combustion pass from the furnace proper into a series 70 of transversely-positioned and horizontally-held heat-conducting pipes C, which are provided with end caps C², so that they may be readily cleaned, these pipes being closed except at a point, as C', from whence the products of combustion are conducted into a suitable groove. These heat-conducting pipes are disposed within the lower portion of the 75 furnace.

Extending through the upper portion of the 80 baking-chamber is a shaft E', supported within suitable bearings, having the extending arms forming a shelf-frame E², there being preferably four such arms, which radiate from the shaft E' and which at their ends revolvably hold the hangers F', forming part of the 85 bake-pans F, which pans are in the form of hanging shelves constructed of a top and lower plate F² F³, separated from each other by the bars F⁴, to which bars the plates are 90 secured, preferably, by rivets F⁵, thus forming an air-space between the plates. The point of suspension is far enough from the supporting-axle E' so that the shelves will freely swing to be retained in a horizontal position in being 95 carried around by the shaft E'.

To facilitate the inspection of the wares upon the shelves, the peep-holes D' are provided, which are covered with mica, glass, or other suitable slides to allow of a ready inspection of the process of baking.

The dome of the oven is provided with a counterbalanced sliding door A², in front of which the shelves pass, so that they can be

readily loaded or unloaded. The sliding door permits a large or small opening, as desired.

The device used to drive the shaft E' consists of a pinion E⁴, which is in mesh with the gear-wheel G' of a spring-motor G of any improved construction. By means of this motor G the hanging pans are revolved at any suitable speed. Now if at any time it should be desired to use but one or two of the shelves, or if the shelves should be unequally loaded, so that the heavier shelves would have a natural tendency to carry the lighter ones upward, I provide a counterbalancing mechanism embodying the rods I, secured to form a part of the shaft E', and upon which rods are adjustably held a series of weights I², as is clearly shown in Fig. 3. By this means the shelf-frame can be nicely counterbalanced with any sort of a weight, so that the motor will have a tendency to run evenly.

In order to regulate the speed of the shelf-frame, I provide a governor H, having a pinion H' in mesh with the gear-wheel E⁵, secured to the shaft E', so that when the latter is rotated a retarded motion is transmitted to the pinion H' and shaft H², carrying said pinion. On this shaft H² is secured a bevel gear-wheel H³, in mesh with the bevel-pinion H⁴, secured on the lower end of the governor-stem H⁵, provided at its upper end with the governor-arms H⁶.

The shelf-frame can be locked at any point by means of a pin I³, working into a bracket I⁴, and this pin coming in the path of the bars I will act as a stop for the shelf-frame.

In order that the speed mechanism may be interchangeable, so that electric, water, or steam power may be used, I provide a motor-shaft L', provided with a fast and loose pulley L², and upon this shaft is secured a pinion L, meshing with a pinion E⁴, secured to the shaft E'. By this means the shaft E' may be thrown out of mesh with the motor if any other suitable power is desired to drive the shelf-frame.

It is quite essential that the pans shall con-

tinuously revolve, and as the motor is driven by a spring and so will run down at the end of a certain time I provide an alarm mechanism, which comprises a follower J, adapted to rest against the outermost coil of the spring G² of the motor G. This follower is secured to a rod J', fitted to slide longitudinally, and is normally pressed against the outer coil of the spring G² by means of a spring J². The outer end of the rod J is further pivotally connected with a lever J³, as is shown in Fig. 4, fulcrumed on a bracket J⁴ and connected by a link J⁵ to the striker J⁶ of the gong J⁷. Now as the spring unwinds and is nearly run down the uncoiling of the spring causes an outward movement of the follower and its connected rod J', so that the lever J³ receives a movement to actuate the link J² to direct the striker J⁶ to ring the gong J⁷ to give the alarm and notice that the motor needs rewinding.

At a suitable point I provide the heating-chamber with an ordinary pyrometer K, having a suitable dial and pointer, as is usual.

Now, having thus described my said invention, what I claim as new, and desire to secure by United States Letters Patent, is—

1. In a bake-oven, the combination with the rotary shaft, of the shelf-frame carried thereby consisting of the arms having the bake-pans suspended at their ends, the counterbalance device mounted on the shaft, whereby the shelf-frame may be counterbalanced, and mechanism for driving the shaft; substantially as described.

2. In a bake-oven, the combination with the reel-shaft, the radial arms on the shaft, the bake-pans suspended on the arms, the radial arms mounted on the end of the shaft outside of the oven, and weights adjustably carried on said arms, and mechanism for driving the reel-shaft; substantially as described.

In testimony whereof I affix my signature in presence of two witnesses.

HERMAN A. SCHOREGGE.
